UNITED STATES PATENT OFFICE.

GEORGE D. BABCOCK, OF PEORIA, ILLINOIS.

GOLF MACHINE AND ATTACHMENT THEREFOR.

Application filed September 18, 1922. Serial No. 588,995.

To all whom it may concern:

Be it known that I, GEORGE D. BABCOCK, a citizen of the United States, residing at Peoria, in the county of Peoria and State of Illinois, have invented new and useful Improvements in Golf Machines and Attachments Therefor; and I do hereby declare that the following is a full, clear, and exact description of the invention, which will enable others skilled in the art to which it appertains to make and use the same.

This invention pertains to socalled golf machines or golf meters, and relates to new and novel means adapted for attachment to machines of this class, both to improve the machines and for adding interest to the game.

Machines for this purpose usually include a portion adapted for rotation to which a golf ball is tethered, and a pointer or indicator to move with respect to sets of figures indicating distances in yards shown to have been traveled by said ball in given drive. Such machines are used to indicate to the player, through said indicator and figures, the distance of practice drives.

Also, by employing a separate diagram or chart of a golf course to which he may refer, he may mentally play over that course while observing the indicated figures on the machine, to determine the length of any drive made, or to be made, and compare it with a known distance indicated on said diagram or chart.

However, machines as commonly provided have no means for permitting the player to observe the interesting effect of a drive of the tethered or captive ball other than that shown by the ball, the said dial and its indicator. In addition, when making drives in connection with a platted golf course the player is required to mentally calculate distances of drives necessary to reach certain objectives, such calculations taking the mind from the game and detracting from the interest thereof.

The object of my invention is that of providing for and placing upon a golf machine a diagram, chart or drawing of a golf course, prepared according to fancy, or platted for any given or proposed golf course, or any part of the same, whereon the tees, greens, fairways, sand pits, the rough, and the like, and various hazards are all clearly shown, the distances platted corre-

sponding with the measurement figures or scales on the machine-dial. Also, an object is to provide an indicator for traversing such diagram, chart or drawing by which the distance of a given drive of the captive ball will be denoted as well as its supposed position of rest after such drive with respect to the greens, fairways, and the like, on the real or ground course.

Another object is that of providing, in connection with such diagram, chart or drawing, a direct-reading scale showing after each drive of the captive ball the distance it has traveled, and a scale showing the distance on the chart said ball has yet to go in a succeeding drive, or drives, to carry the indicator to one or more objective points charted.

My invention therefore seeks to furnish, in a golf machine, a diagram or chart upon which any proposed or known golf course is reproduced upon a smaller scale than an actual ground course, an indicator, and mechanism operated by the ball in its flight for moving the indicator across the diagram a distance or distances in exact proportion to the travel of said captive ball. Also, to furnish a diagram or chart of a golf course, and a direct-reading scale, one adapted to move with respect to the other, so designed that the exact distance of drives made and to be made are directly read. Furthermore, an object is that of providing a diagram or chart of a golf course, and a scale and indicator adapted for movement with respect to said diagram or chart furnished as attachments for a golf machine without respect to its form or type.

In the appended drawings:

Figure 1 is a front elevation of parts of a golf machine showing my invention.

Figure 2 is a plan of a scale-carrying dial, and an associated part or ring having thereon the representation of a portion of a golf course.

Figure 3 is a plan of other parts or rings similar to that shown in Figure 2.

Figure 4 is a transverse sectional elevation of the machine shown in Figure 1, and

Figure 5 is a plan of a slightly different arrangement of parts shown in Figures 1 and 2.

Machines for golf practice are fairly well known and I shall therefore merely describe sufficient structure of a machine to illustrate

the use and purpose of my invention in connection therewith.

1 designates an upright, for example, supporting a dial-carrying head 2, and 1' is a member rotatably mounted upon said upright. Journaled centrally in the head is a shaft or arbor 3, Figure 4, suitably operated through any desired speed reducing gear, not shown, by means of a shaft 6 5 journaled in an upright position in the head 2 and carrying at its lower end a gear 7. In mesh with said gear 7 is a gear 8 secured on the described rotatable member 1'. Attached to one end of the member 1' is a cable 10 15 9 to whose opposite extremity a golf ball 9' is secured.

Golf machines are usually so designed that by means of reducing gear of one type or another, the distance actually traveled 20 by the captive ball is shown upon a dial or other scale by means of a hand or pointer, the distance between any two division marks of said dial being proportional to a given distance of actual travel or flight of said 25 ball, all of which is made use of in connection with my invention, now to be described.

The numeral 10 indicates a dial mounted upon the shaft or arbor 3, being secured thereon by any suitable means, I having 30 shown in this instance, as one method, a screw 10² passing through said dial and entering said shaft. There may be sufficient friction between the dial and shaft to secure positive rotation of said dial with the shaft, 35 while at the same time permitting the said dial to be turned with respect to the shaft on occasion, or, the shaft itself may be so mounted that it and the dial may be turned with respect to the gear that operates said 40 shaft, the purpose of which will appear.

Adjacent the dial is a support for receiving upon it the charted representation of a golf course or portion thereof, said support, in this instance, taking the form of a ring 45 11 as a matter of convenience, said dial lying within the same. An indicator 10' extends from the edge of the dial for traveling over the chart, and, by choice merely, may represent a golf ball. There may be 50 more than one of the rings 11 according to the extent of golf course to be represented.

The scale on which the drawing or chart is produced must agree with the distance scale on the dial in yards, of course, so that in a 55 100 yard drive of the ball 9' that exact distance will be shown in the travel of the indicator upon said drawing or chart as scaled, the reading of the dial agreeing therewith.

60 Upon the ring shown in Figures 1 and 2 there is represented for example, a "tee" at 12, at 13 "the rough", at 14 "the fairway", at 15 "the green" and so on, which may be a course prepared according to fancy or it 65 may be one actually reproduced from a

known course, while in Figure 3 other ground-layouts are represented. The several rings as a whole may show an entire golf course or one ring surface may carry the entire course depending upon the scale 70 of the drawing or chart and the ratio of reduction of movement between the ball 9' and the indicator 10'.

It is desirable to provide means for permitting easy removal of the ring or rings 75 so that they may be reversed in position or replaced by others and to this end I provide some such means as is shown in Figures 1 and 4, though any other device may be employed. For instance, 16 is a ring having a series of spring wires 16' attached to it at 80 intervals for gripping, frictionally, the outer surface of the head 2 as shown, said wires 16' including extensions or legs 17 for abutting upon the ring and retaining it 85 in position.

Returning now to the dial 10, it is observed that there are two columns of figures 90 arranged thereupon reading from 0 to 590, preferably progressing by tens and expressing yards. It is observed, further, that the "0" of both columns lies upon the same 95 radial line and that the figures progress in value in opposite directions. Now, while the use of these two columns is not new in a golf machine, yet because the dial having the figure columns denoted thereon rotates with respect to the ring 11 a new result is 100 produced in that thereby the player is always enabled to determine by a glance at the dial, and by direct reading, the exact distance his ball may have been driven, also the number of yards he has still to drive his ball to reach a given position. For example, in Figure 1 the indicator 10' is at 105 the starting tee denoted at 12. The player by observing the outer scale of figures reads 140 yards as the actual distance his ball 9' must be driven in order that the machine shall register a drive that will carry said indicator beyond the "rough" indicated at 13.

Now, if his subsequent drive of the ball 9' has been such as to have carried the indicator 10' beyond the rough 13 and upon the fairway 14, see Figure 2, then not only is he enabled to read in the outer column the distance in yards from his then position on the fairway to the green at 15 which, as 110 shown by that column is 250 yards, but he may also read in the inner column the distance covered in his last drive, 140 yards. The player thus has exact figures in yards 115 reading directly and always upon the course represented. In further drives the player, having finished the course shown in Figures 1 and 2, may reverse the position of the ring 11 on the machine or he may insert another, as the case may be. Upon making this 120 change the indicator 10' is placed upon the 125 130

new starting tee, as permitted by the movement of the dial with respect to the shaft or arbor 3 described earlier herein, and the drives or plays may be continued.

- 5 The drawings or diagrams and the indicator to work in conjunction therewith, together with the scale, may be readily adapted for use on any type of golf machine and sold as attachments therefor, or
 10 I may construct a machine of which the above are parts.

It has been stated herein that the diagram or chart on the ring 11 and the dial 10 rotate with respect to one another. In Figures 15 1 and 2 as described, the said dial 10 rotates while the diagram or chart of the ring 11 is fixed. In Figure 5, however, I have shown the reverse of this. The two previously described columns of figures are now 20 on a fixed ring or annulus 18, corresponding to 11, instead of on a central rotating dial as in the other figures, and the indicator 19 corresponding to 10' is likewise fixed in position and extends inwardly to overhang 25 the area enclosed by said ring or annulus. Also, the charted golf course is placed upon a central rotating disc 20 beneath the indicator and rotates with respect to it.

Certain advantages attend either form 30 and either form therefore may be used and readily adapted to such a type of machine as is illustrated herein; and the same general principles are applicable to any other machine, merely requiring such slight changes 35 as may be necessary to accommodate a given type.

I do not wish to be understood as limiting myself to the exact structures herein 40 shown since various minor changes may be readily made which will serve the same purpose.

I claim:

1. A machine for the purposes named including, in combination, a scaled chart reproducing in miniature the ground layout of an outdoor game course including a representation of the physical characteristics of ground surface of said course, or part thereof, and an indicator or pointer therefor, mechanism adapted for imparting movement to one of the described parts with respect to the other, a captive ball tethered to said mechanism adapted in flight to impart movement to the movable part and speed reducing gearing included in said mechanism arranged whereby the actual distance of travel of a ball upon the course is indicated at said chart in accordance with the scale upon which the latter is produced.

2. A machine of the type and for the purposes named including, in combination, a scaled chart reproducing in miniature the ground layout of an outdoor game course 65 including a representation of the physical

characteristics of ground surface of said course, an indicator or pointer therefor, mechanism operatively connected to one of the described parts for moving it with respect to the other, a scale at said indicator 70 or pointer each of whose distance denoting divisions corresponds in value with a given distance platted on said chart, and a captive ball tethered to said mechanism including speed reducing gearing arranged 75 whereby the actual distance traveled by a ball upon said course is represented on said chart by said pointer in direct proportion to such actual travel and according to the scale on which such chart is produced. 80

3. A machine of the type and for the purposes named including, in combination, a platted chart reproducing in miniature the ground layout of an outdoor game-course 85 to scale, the same including a representation of the physical characteristics of the ground surface of said course, an indicator or pointer for use in conjunction therewith, mechanism operatively connected to one of the described parts for moving it with respect to the other, a series of figures separate from the chart for scaling distances on said chart, one of the last named elements 90 also being movable with respect to the other through said mechanism, and a captive ball tethered to the mechanism, the latter including speed reducing gearing by which the actual distance-travel of a ball upon 95 the course is reproduced on the chart by said indicator or pointer in the travel of said captive ball. 100

4. A machine of the type and for the purposes named including in combination a platted chart representing in miniature the ground layout of an outdoor game-course, an indicator or pointer for use in conjunction with said chart, one of the described parts being movable, mechanism 105 operatively connected to the movable part including a reducing gearing; a captive ball tethered to said mechanism; and an element having thereon two scales disposed adjacent the said chart reading in opposite directions, the divisions on said scales representing on said chart known distances on the 110 said game-course. 115

5. A machine of the type and for the purposes named including, in combination, a platted chart representing the ground layout of an outdoor game-course, an indicator or pointer for use in conjunction therewith including two columns of figures disposed adjacent said chart to be read upon the same, the figures of the columns reading 120 in opposite directions from a common position on the chart, the latter and the indicator or pointer with its figure columns adapted to move one with respect to the other, mechanism operatively connected to 125 130

the movable element of the described parts, and a captive ball arranged to impart movement to said mechanism.

6. A machine of the type and for the purposes named including, in combination, a platted chart representing the ground layout of an outdoor game-course, an indicator or pointer for use in conjunction therewith including two columns of figures disposed adjacent said chart to be read upon the same, the figures of the columns reading in opposite directions from a common position on the chart, the latter and the indicator or pointer with its figure columns adapted to move with respect to one another, the indicator or pointer and figure columns being fixed relatively, mechanism operatively connected to the movable element of the described parts, and a captive ball arranged to impart movement to said mechanism.

7. The combination with a machine for playing golf including mounted movable mechanism, a ball tethered to said mechanism adapted to impart movement thereto, and an indicator operated by the mechanism, a chart having thereon the representation of a golf course traversed by said indicator, including a representation of the physical characteristics of ground surface of said course, and a measurement scale movable with the indicator to represent the actual travel of said ball.

8. The combination, in a golf machine, of an indicator, a mounted chart at said indicator representing a playing course, one of the described parts adapted for movement, a captive ball operatively connected to the movable part, and a direct reading scale fixed with respect to the indicator and lying contiguous to said chart for denoting thereon the distance of a succeeding drive of the ball necessary to reach an objective.

45 9. The combination, in a golf machine, of an indicator, a mounted chart at said indicator representing a playing course, one of the described parts adapted for movement whereby the indicator will denote positions on said chart, a captive ball arranged and adapted to impart such movement, two direct reading figure columns fixed with respect to the indicator, lying contiguous to said chart, and reading in opposite directions, one for denoting the distance of a drive of the ball necessary to reach an objective, the other denoting the distance covered in a completed drive of said ball.

10. In combination with a golf machine including a captive ball and an indicator to which motion is transmitted by the ball in its flight, of a chart mounted on the machine representing a course to be traversed by said indicator, and a direct-reading scale movable with the indicator in-

dicating at the end of each drive of said ball the distance of a succeeding drive necessary to reach an objective.

11. In combination with a golf machine, including a captive ball, and an indicator to which motion is transmitted by the ball in its flight for reproducing on said machine the extent of travel of said ball in each drive thereof, a direct-reading scale movable with the indicator arranged to show in direct reading on the machine at the end of each movement of the indicator the distance necessary to drive the ball to reach an objective.

12. In combination with a golf machine, including a captive ball and an indicator to which motion is transmitted by the ball in its flight for reproducing on said machine the extent of travel of said ball in each drive thereof, a scale movable with the indicator arranged to show in direct reading at the end of each movement of said indicator the distance of necessary travel of the ball to reach an objective.

13. In combination with a golf machine, including a captive ball and an indicator to which motion is transmitted by the ball in its flight for reproducing on said machine the extent of travel of said ball in each drive thereof, a dial movable with the indicator having two sets of figures reading in opposite directions, one of said sets showing in direct-reading the distance of necessary travel of the ball in yards to reach an objective, the other set of figures showing in direct-reading the distance traversed by the ball in preceding drives.

14. A golf machine including in its construction a captive ball, a chart of a golf course, an indicator operated by the ball, the same denoting on said chart the actual travel of the ball, and a dial adapted for rotation with respect to the chart and having thereon a scale, said scale adapted by direct-reading to indicate the distance of actual travel of the ball and the drive to be imparted thereto necessary to carry it to an objective.

15. A golf machine including in its construction a captive ball, a chart of a golf course, an indicator operated by the ball, the same denoting on said chart the actual travel of the ball, and a dial rotatable with the indicator and having thereon a direct reading scale adapted and arranged to indicate from any position of rest of said indicator the distance of travel in yards necessary to be made by the ball to carry said indicator to an objective point on said chart.

16. A golf machine including in its construction a captive ball, a chart of a golf course, an indicator to denote on said chart the actual travel of the ball in a given drive, and a dial rotatable with the indicator and having thereon two distance-indicating-

scales reading in opposite directions from a given starting position of said indicator, one showing by direct reading the length of a drive of said ball necessary to carry 5 said indicator from a given position thereof to an objective point on the chart, the other showing the length of a drive of the ball previously made.

17. An attachment for a machine for playing a game including a mounted part comprising a platted chart of a game course including denoted playing positions, and a part including a measurement scale fixed relatively thereto positioned adjacent the 15 chart whereby to indicate to a player at said machine measured distances thereon, one of the described parts being adapted to travel with respect to the other.

18. An attachment for a machine for playing a game including a captive ball, said attachment including a platted chart of a game course including denoted playing positions, and a part including a measurement scale fixed relatively thereto positioned adjacent the chart whereby to indicate to a player at said machine measured distances thereon, one of the described parts being adapted to move with respect to the other, the movable part being operatively connected to the said ball to be moved thereby, the second named of the two parts together with said scale adapted for denoting upon the chart in exact ratio the distance of actual travel of said captive ball in its 35 flight.

19. An attachment for a machine for playing a game including a chart showing a playing field, and a part adapted for position adjacent said chart movable with re-

spect thereto including two measurement 40 scales reading in opposite direction but movable in the same direction adapted for use in conjunction with denoted positions at said chart.

20. An attachment for a machine for 45 playing a game comprising a chart showing a playing field, a part adapted for position adjacent said chart movable with respect thereto including a measurement scale adapted for use in conjunction with denoted 50 positions at said chart, and an indicator portion extending from the said part opposite the character on said scale denoting the least value.

21. An attachment for a machine for 55 playing a game comprising a chart of ring form showing a playing field, and a part adapted to lie within the chart, rotatable with respect to it, and having a measurement scale arranged at its marginal edge 60 adjacent the said chart, and an indicator portion extending from the said marginal edge opposite the character of said scale denoting the least value.

22. In combination with a machine for 65 playing a game including a captive ball, an attachment therefor including a chart representing a game-course, and an indicator or pointer, one of the described elements adapted to travel with respect to the other, said ball having operative connection with the movable element for driving it, and two measurement scales fixed with respect to the indicator or pointer, reading in opposite directions therefrom, and lying adjacent to and readable upon the said chart.

In testimony whereof I affix my signature.
GEORGE D. BABCOCK.
